(57) **CLAIM**

The ornamental design for a protection cover for a window curtain chain, as shown and described.

DESCRIPTION

FIG. 1 is a perspective view of a protection cover for a window curtain chain;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is the enlarged front view of the protection cover for a window curtain chain shown in a condition of use; and,

FIG. 9 is an enlarged front view of the protection cover for a window curtain chain shown in an alternative condition of use.

The broken lines in the drawings represent unclaimed environmental subject matter.
